AUTOMATIC FILLING CONTROL MEANS

Charles L. Keller, Cincinnati, Ohio, assignor to
The Richardson Company, Lockland, Ohio, a
corporation of Ohio

Application February 2, 1940, Serial No. 316,992

9 Claims. (Cl. 136—178)

The general object of my invention is the provision of a non-overfill device of simple but effective character which does not complicate nor increase the cost of a storage battery cell cover, and which is readily renewed. The disclosure of this case is related to the disclosures of my co-pending application Serial No. 276,826, filed June 1, 1939, now matured into Patent No. 2,233,081 dated February 25, 1941, in that a weight operated valve member is employed to close a gas vent opening, the valve member being positively moved by the filler cap. It is also related to the disclosure of my copending application Serial No. 304,590, filed November 15, 1939, now matured into Patent No. 2,261,032 dated October 28, 1941, in that a filler well construction is employed in which the tubular extension rises somewhat upwardly within the well leaving an annular depression thereabout, which depression houses the valve member.

I accomplish the several objects of my invention as recited above, and other will be apparent to the skilled worker in the art upon reading this specification by that certain construction and arrangement of parts of which I shall now describe certain exemplary embodiments. Reference is made to the drawing wherein:

Figure 1 is a partial vertical sectional view taken longitudinally through the cell of a storage battery and the cell cover thereof.

Fig. 2 is a sectional view through a portion of the filler well taken along the lines 2—2 of Fig. 1.

Fig. 3 is a partial sectional view of the cell cover showing the relationship of parts when the filler cap is in place.

Fig. 4 is an elevational view of a filler cap suitable for use in one form of my invention.

Fig. 5 is a partial sectional view through a cell cover showing a modified form of the invention.

Fig. 6 is a horizontal section of a portion of the 40 filler well as shown in Fig. 5.

Fig. 7 is a partial vertical section showing the relationship of parts of the structure of Figs. 5 and 6 when the filler cap is in place.

In Fig. 1, 1 indicates the walls of a battery box containing the usual plate assembly 3 and electrolyte 4. The cell has a cell cover 5 held in place by the usual sealing compound 7, and perforated to permit the passage of the terminal lugs of the plate assembly. A filler well 8 is formed in the body of the cell cover and has a bottom 9 from which a tubular extension 10 depends to a desired maximum electrolyte level. The tubular extension is, of course, open through the bottom of the well, and projects upwardly

above the bottom as at 11, thus providing an annular depression 12 within the well. The well walls are provided internally with threads 13 or other means whereby a filler cap may be engaged therein. A perforation 14 is made through the bottom of the well exterior to the tubular extension so as to vent gas from the space above the electrolyte. The annular depression 12 is, in the present invention, a raceway for a ball which acts as the valve member. The bottom of the raceway is formed so as to be slanting, i. e. its lowest point is adjacent the perforation 14 and its highest point substantially directly opposite. Thus a ball placed in the raceway will roll around it until it comes to rest in a position covering the perforation 14. To increase the positiveness of the valve action I prefer to form adjacent the perforation a slight conforming depression (15 in Fig. 3) in which the ball will come to rest and from which it is not likely to be dislodged by ordinary vibration. The ball is indicated at 16 and is formed of some substance resistant to the action of the storage battery electrolyte. It thus may be made of hard rubber or other insulating material; but I prefer to form it of antimonial lead or metal covered with antimonial lead, so that its mass may be as great as possible. A threaded ring 17 may be placed in the well as shown in Fig. 1 to act as a retainer for the ball.

When the filler cap is removed and the ball is covering the perforation 14, the introduction of water or electrolyte through the tubular extension 10 will cause the electrolyte level to rise in the cell until it reaches the bottom of the tubular extension. Then, since the gas vent perforation 14 is closed by the ball 16, the electrolyte will rise rapidly within the tubular extension 10, thus giving an overfill signal. The ball may, if desired, be made heavy enough to counterbalance a column of liquid for the full length of the tubular extension 10, thus making it impossible to overfill the cell.

At the conclusion of the filling operation the insertion of the filler cap will open the valve by reason of a construction now to be explained. In Fig. 3 I have shown the filler cap 17a having a hollow body and a threaded extension 18 to engage in the filler well. A gas vent perforation 19 communicates with the hollow interior of the body; and the usual splash washer 20 may be provided as will be well understood. The extension 18 is provided with a finger 21 which enters the annular depression 12 and moves the ball therein. If a single lead thread is provided in the filler

well and on the filler cap, a single finger 21 may be employed, and will be positioned in such a way as to lie above the perforation 14 when the filler cap is turned home. As the filler cap is screwed into position, the finger 21 moves the ball sideways from the depression 15, thus opening the perforation 14 for gas venting purposes. Since the finger 21 lies above the perforation it will be impossible for the ball to roll around the raceway and come to rest again in the seat 15. The finger 21 may be made wide enough to compensate for the use of a resilient washer (not shown) on the filler cap or for differences in the manner in which the filler cap is turned home.

Where the filler well and filler cap are provided with a double lead thread so that the finger could occupy one of two positions, it becomes necessary, as shown in Fig. 4, to provide the filler cap 22 with two oppositely disposed fingers 23 and 24.

Where it is deemed desirable to have a finger contact the ball prior to the engagement of the threads on the filler cap and filler well (and where this cannot be done if the finger is short enough to clear the high part of the raceway when the filler cap is fully turned in), it is within the scope of my invention to groove the higher part of the raceway as at 25. The groove will be narrow enough not to accept the ball and it will terminate away from the actual valve seat on either side thereof, as clearly shown in Figs. 5 and 6. This permits the use of a finger or the like which is very long. Instead of a finger an annular extension 26 may be formed on the filler cap 27 as shown in Fig. 7; and this annular extension may be cut away as at 28 to accept the ball. The annular extension 26 as well as the fingers 21 or 23 and 24 are relatively thin and do not have much tendency to displace water or electrolyte in the filler well if the filling is carelessly done. With the construction shown in Figs. 5, 6 and 7 the filler cap may be engaged with the ball prior to the actual engagement of the threads of the filler cap and filler well; and the ball will rotate around the raceway as the filler cap is being turned in.

While I have illustrated types of structures in which the outer walls of the well are threaded, following the teachings of my Patent No. 2,261,032, it will be within the skill of the worker in the art to modify the filler cap to provide a central threaded post or extension engageable with threads in the upwardly extending portion 11 of the tubular extension 10, the finger or fingers in this case lying outside the threaded extension of the filler cap.

Within the purview of these teachings, modifications will be possible without departing from the spirit of my invention. Having thus described my invention in an exemplary form, what I claim as new and desire to secure by Letters Patent, is:

1. A cell cover with walls defining a well with a bottom, a hollow, fixed tubular extension on said well terminating downwardly at a desired maximum electrolyte level, a portion of said tubular extension being directed upwardly within said well so as to leave within said well an annular recessed depression for the acceptance of a valve member, said annular depression having a floor which is slanting from one side to the other so that said valve member when in the form of a ball will roll around said floor and come to rest at its lowest portion, there being a gas venting perforation through said floor at said

lowest portion exterior to said tubular extension.

2. A cell cover with walls defining a well with a bottom, a hollow, fixed tubular extension on said well terminating downwardly at a desired maximum electrolyte level, a portion of said tubular extension being directed upwardly within said well so as to leave within said well an annular recessed depression for the acceptance of a valve member, said annular depression having a floor which is slanting from one side to the other so that said valve member when in the form of a ball will roll around said floor and come to rest at its lowest portion, said floor having a further depression in the form of a valve seat at its said lowest portion, there being a perforation through the bottom of said depression at said last mentioned portion exterior to said tubular extension.

3. A cell cover with walls defining a well with a bottom, a hollow, fixed tubular extension on said well terminating downwardly at a desired maximum electrolyte level, a portion of said tubular extension being directed upwardly within said well so as to leave within said well an annular recessed depression for the acceptance of a valve member, said annular depression having a floor which is slanting from one side to the other so that said valve member when in the form of a ball will roll around said floor and come to rest at its lowest portion, said floor having a further depression in the form of a valve seat at its said lowest portion, there being a perforation through the bottom of said depression at said last mentioned portion exterior to said tubular extension, a valve member in the form of a ball and means in said filler well to retain a ball valve member in said annular depression.

4. A cell cover with walls defining a well with a bottom, a fixed, hollow tubular extension on said well terminating downwardly at a desired maximum electrolyte level, a portion of said tubular extension being directed upwardly within said well so as to leave within said well an annular recessed depression for the acceptance of a valve member, said annular depression having a floor which is slanting from one side to the other so that said valve member when in the form of a ball will roll around said floor and come to rest at its lowest portion, said floor having a further depression in the form of a valve seat at its said lowest portion, there being a perforation through the bottom of said depression at said last mentioned portion exterior to said tubular extension, a valve member in the form of a ball, means in said filler well to retain said ball valve member in said annular depression, and a vented filler cap engageable in said filler well and having a finger positioned for moving said ball away from said valve seat when said filler cap is engaged in said filler well.

5. In a cell cover, walls defining a filler opening in the form of a well with a bottom, a fixed tubular member open through said bottom, extending downwardly therefrom to a desired maximum electrolyte level, and extending upwardly within said well to the extent of defining an annular depression in said well surrounding said tubular member, the floor of said depression being disposed slantingly whereby a ball valve member under gravity will come to rest at a certain portion of said floor, a perforation through said floor at said portion and adapted to be closed by said ball, a ball valve member, and a filler cap having a finger thereon, posi-

tioned so as to move said ball from said perforation when the filler cap is engaged in said filler well.

6. In a cell cover, walls defining a filler opening in the form of a well with a bottom, a fixed tubular member open through said bottom, extending downwardly therefrom to a desired maximum electrolyte level, and extending upwardly within said well to the extent of defining an annular depression in said well surrounding said tubular member, the floor of said depression being disposed slantingly whereby a ball valve member under gravity will come to rest at a certain portion of said floor, a perforation through said floor at said portion and adapted to be closed by said ball, a ball valve member, and a filler cap having a finger thereon, positioned so as to move said ball from said perforation when the filler cap is engaged in said filler well, said floor in portions other than said lowest portion being provided with a groove to accommodate said finger.

7. A cell cover having walls defining a filler opening in the form of a well with a bottom, a fixed tubular extension, open through said bottom, and depending therefrom to a desired maximum electrolyte level, said bottom being formed to provide a valve seat portion and a raceway for a ball valve, substantially following the contour of said walls, and so disposed as to cause said valve to roll by gravity to said valve seat portion, an opening through said bottom at said valve seat portion exterior to said tubular extension, a ball valve member, and means within said well to retain a ball valve in said raceway.

8. A cell cover having walls defining a filler opening in the form of a well with a bottom, a

fixed tubular extension, open through said bottom, and depending therefrom to a desired maximum electrolyte level, said bottom being formed to provide a raceway for a ball valve, substantially following the contour of said walls, and so disposed as to cause said valve to roll by gravity to a valve seat portion, an opening through said bottom at said valve seat portion exterior to said tubular extension and means within said well to retain a ball valve in said raceway, and a ball valve member, said well being provided with threads, and a threaded filler cap engageable therein, said filler cap and well having single lead threads and said filler cap being provided with a finger to displace said ball when said filler cap is in position in said filler well.

9. A cell cover member having walls defining a filler opening in the form of a well with a bottom, a fixed tubular extension, open through said bottom, and depending therefrom to a desired maximum electrolyte level, said bottom being formed to provide a raceway for a ball valve, substantially following the contour of said walls, and so disposed as to cause said valve to roll by gravity to a valve seat portion, an opening through said bottom at said valve seat portion exterior to said tubular extension and means within said well to retain a ball valve in said raceway, and a ball valve member, said well being provided with threads, and a threaded filler cap engageable therein, said filler cap and well having a double lead thread, and said filler cap having a pair of fingers to displace said ball when said filler cap is engaged in said filler well.

CHARLES L. KELLER.
